UNITED STATES PATENT OFFICE.

REES H. LEMMON, OF LONG BEACH, CALIFORNIA.

PUMP PLUNGER.

Application filed March 22, 1926 Serial No. 96,485.

This invention relates to a pump plunger and is more particularly directed to a pump plunger adapted for use in oil well pumps for the pumping of oil and the like from wells.

5 An object of this invention is to provide an oil well pump plunger in which means are provided for lubricating bearing surfaces of the pump plunger with the oil pumped from the well and in which pump a plurality of 10 operable expandible packing members are provided and adapted to be expanded outwardly by means of hydraulic pressure.

Other objects and advantages of this invention will be apparent from the following 15 detailed description of a preferred embodiment thereof as illustrated in the accompanying drawings, in which drawings:

Figure 1 is a side elevation of an oil well pump taken partly in section and illustrating 20 the pump plunger embodying this invention.

Figure 2 is a fragmental side elevation of the oil well pump assembly illustrated in Figure 1 and illustrating the pump plunger in vertical mid-section.

25 Figure 3 is an end elevation taken substantially on the line 3—3 of Figure 2.

Figure 4 is an end elevation taken substantially on the line 4—4 of Figure 2.

In the preferred embodiment of this invention illustrated in the accompanying drawings, 1 illustrates a casing such as is ordinarily employed in oil wells. A tubing or fluid string 2 is mounted concentrically within the casing 1 and a pump barrel 3 is mounted concentrically within the tubing 2 at the lower end thereof and is removably supported at its lower end 4 at a barrel anchor 5 and is provided with an expandible packing member 6 at its upper end, which pump barrel 30 assemby is more particularly described in my copending application, filed March 22, 1926, Serial No. 96,486. A pump plunger 7 is mounted to reciprocate within the barrel 3 and is suspended therein on sucker rods 8 which are adapted to be reciprocated by any suitable or desirable means (not shown).

The pump plunger 7 is preferably of the following construction and comprises a tubing 9, to the upper end of which tubing 9 a working valve cage 10 is screw-threaded as illustrated at the threads 11. A ball valve member 12 is mounted within the cage 10 on a seat 13. The cage 10 is secured to the sucker rods 8 at a sucker rod coupling 14. A sleeve 15 is screw-threaded to the lower end of the plunger 7 at the threads 16. Secured

to the lower end of the sleeve 15 at the threads 17 is a valve seat supporting member 18 which has a central bore formed therethrough and supports at its upper end a valve seat 19 upon which a ball 20 is adapted to seat. A pin 21 is passed through the sleeve 15 for the purposes of retaining the ball 20.

Means are provided for packing the plunger 7 outwardly against the barrel 3, which 65 means are preferably of the following construction:

A plurality of rings 22, formed of any desirable packing material, are mounted on the plunger 7. The rings 22 are of larger interior bore than the exterior diameter of the tubing 9 so as to provide a space between the rings 22 and the plunger 7. A plurality of radially opposed slots 23 are formed in the tubing 9 immediately behind the rings 22 so as to provide a communication between the central passage of the tubing 9 and the space provided between the rings 22 and tubing 9 so as to permit the fluid pumped, such as oil to flow into this space so that when the pump 80 is operated to pump the oil from the well, the fluid admitted to the space between the rings 22 and the tubing 9 will expand the rings 22 outwardly against the barrel 3 so as to provide a fluid tight connection. The rings 22 engage the shoulder 24 formed at the upper end of the sleeve 15 at one end and are secured in position by means of a collar 25 screw-threaded to the tubing 9 at threads 26.

Spaced on the packing assembly provided 90 by the rings 22 on the plunger 7 is a second packing assembly 27 which may comprise cups 28 or any other desired packing construction. The cups 28 are mounted upon the plunger 7 and are provided with spacers 29 and are maintained in position by means of an upper spacing collar 30 which is screw-threaded to the sleeve at the upper end and by means of a collar 31 screw-threaded to the tubing 9 at the lower end. A lock collar 32 100 is screw-threaded to the plunger 7 in position to engage the collar 30 to lock the same in position. The space provided between the collars 25 and 31 provides an oil receiving chamber 33 into which the oil pumped by the plunger is admitted through spaced slots 34 formed in the tubing 9. The oil pumped through the plunger flows outward through the slots 34 into the receiving chamber 33 and lubricates the packings provided by the 110 rings 22 and cups 28 so as to reduce the friction between the packing members and the

barrel 3 and consequently to reduce the wear upon the said packing members. The oil in the chamber 33 also provides a fluid tight pump which prevents leakage of the oil past the packing members upon operation of the pump so that if on the up-stroke of the plunger 7 the packing 28 should leak, the oil will tend to flow through the slots 34 into the bore of the plunger 7 rather than past the packing rings 22 and likewise if on the down-stroke of the plunger 7 the rings 22 should leak, the oil will tend to pass by the rings 22 and through the ports 34 into the bore of the plunger 7 and not by the packing 15 cups 28.

Having fully described a preferred embodiment of my invention, it is to be understood that I do not wish to be limited to the exact details herein set forth which may obviously be varied without departing from the spirit of my invention as set forth in the appended claims.

I claim:

1. A pump plunger comprising a tube, a 25 working valve secured to the upper end of the tube, a working valve secured to the lower end of the said tube, a plurality of packing rings of greater interior diameter than the exterior diameter of the said tube 30 mounted on the tube, a retaining collar screw-threaded on the said tube and engaging the said rings, slots formed in the said tube behind the said rings for admitting fluid pressure outward to the space provided by 35 the rings of the tube for expanding the said rings, a second packing assembly spaced from

and above the said packing rings, and a slotted section of the said tube intermediate the said packing assemblies, placing the space between said assemblies in communication 40 with the bore of said plunger.

2. A pump plunger comprising a tube, upper and lower working valves secured to the opposite ends of the said tube, spaced retaining collars screw-threaded to the said tube near the intermediate section thereof, packing assemblies mounted on the said tube between the said retaining collars and working valves, the upper assembly comprising 45 cups and the lower assembly rings, and a slotted section of the said tube intermediate the said packing assemblies, placing the space between said assemblies in communication with the bore of said plunger.

3. A valved pump plunger comprising a 50 tube, a packing assembly including a plurality of packing rings of greater interior diameter than the exterior diameter of the said tube, a retaining collar screw-threaded on said tube and engaging said rings, slots 55 formed in said tube behind said rings for admitting fluid pressure outward to the space provided between the rings and the tube for expanding said rings, a second packing assembly spaced from and above said packing 60 rings, and a slotted section of said tube intermediate the said packing assemblies placing the space therebetween in communication with the bore of said tube.

Signed at Los Angeles, California, this 12⁷⁰ day of March, 1926.

REES H. LEMMON
